PLATE OR SIMILAR ARTICLE

John H. Reiser, Downey, Calif., assignor to Wallace China Co., Ltd., Los Angeles, Calif., a corporation of California

Filed Mar. 7, 1960, Ser. No. 59,645

Term of patent 14 years

(Cl. D44—15)

The figure is a plan view of a plate of conventional configuration, showing my new design.

The lined shading indicates areas of contrasting color.

I claim:

The ornamental design for a plate or similar article, substantially as shown and described.
